US00D928429S

(12) United States Design Patent (10) Patent No.: US D928,429 S
Ou Yang (45) Date of Patent: * Aug. 17, 2021

- (54) ULTRAVIOLET STERILIZER FOR CHOPPING BOARD
- (71) Applicant: SHENZHEN UVLED OPTICAL TECHNOLOGY CO., LTD, Shenzhen (CN)
- (72) Inventor: Chenyi Ou Yang, Yongzhou (CN)
- (73) Assignee: SHENZHEN UVLED OPTICAL TECHNOLOGY CO., LTD., Shenzhen (CN)
- () Term: 15 Years
- (21) Appl. No.: 29/703,132
- (22) Filed: Aug. 23, 2019
- (51) LOC (13) Cl. 15-05
- (52) U.S. Cl. D32/1
- (58) Field of Classification Search

(57) CLAIM

The ornamental design for an ultraviolet sterilizer for chopping board, as shown and described.

DESCRIPTION

FIG. 1 is a front, top and left perspective view of an ultraviolet sterilizer for chopping board showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict portions of the ultraviolet sterilizer for chopping board in which the design is embodied that form no part of the claimed design.

1 Claim, 5 Drawing Sheets
